CLAIM

The ornamental design for a combined cushion and carrying bag, as shown and described.

DESCRIPTION

FIG. 1 is a front elevational view of a combined cushion and carrying bag showing our new design;

FIG. 2 is a right side elevational view thereof (the left side elevational view being a mirror image of FIG. 2);

FIG. 3 is a rear elevational view thereof;

FIG. 4 is a top plan view thereof;

FIG. 5 is a bottom plan view thereof;

FIG. 6 is a perspective view thereof, showing the cushion in open position;

FIG. 7 is a perspective view thereof, showing the combined cushion and carrying bag in folded position for carrying;

FIG. 8 is a front elevational view of a combined cushion and carrying bag showing a modified version of our new design;

FIG. 9 is a right side elevational view thereof (the left side elevational view being a mirror image of FIG. 9);

FIG. 10 is a rear elevational view thereof;

FIG. 11 is a top plan view thereof;

FIG. 12 is a bottom plan view thereof;

FIG. 13 is a perspective view thereof, showing the cushion in open position; and

FIG. 14 is a perspective view thereof, showing the combined cushion and carrying bag in folded position for carrying.
